UNITED STATES PATENT OFFICE.

VANCE SHEARER, OF NEW YORK, N. Y.

IGNITION TIMER FOR INTERNAL-COMBUSTION ENGINES.

Application filed May 27, 1921. Serial No. 472,943.

To all whom it may concern:

Be it known that I, VANCE SHEARER, a citizen of the United States, residing at the borough of Manhattan, city, county, and 5 State of New York, have invented an Improvement in Ignition Timers for Internal-Combustion Engines, of which the following is a specification.

My invention relates to timers such as 10 employed to control the ignition in multiple cylinder internal combustion engines, and while having other and more general fields of usefulness, is well adapted and designed for use in the ignition system of the well 15 known Ford type of automobile.

In all devices of this character, so far as I am aware, their life is comparatively short, owing to the pitting or burning of the brass segments, and contact brush, or 20 carbonizing of the condensite raceway of the timer, the current being continuously carried by the movable contact or brush during its travel around the raceway.

The principal object of my present invention is to overcome this difficulty, and 25 greatly lengthen the life of the timer, while increasing its efficiency, by the employment of means for making and breaking the electric circuit in such manner that the movable contact or brush does not receive the current until it reaches and is upon one 30 end of a fixed contact, the circuit being broken as the brush reaches the opposite end of such fixed contact and before it passes 35 off the same, the make and break of the electric current spark being controlled entirely by such means. The contact points are made of alloy capable of standing the high voltage and amperage of electricity traveling 40 therethrough without pitting or burning the same. Another object is to provide means for equalizing the breaker contact at all times regardless of any end play that may occur in the cam shaft. The details of 45 construction and operation of my invention are hereinafter particularly set forth, in which other features of novelty and utility will be observed.

In the accompanying drawing:

50 Figure 1, is an inner end view of a timer constructed in accordance with my invention, the cam shaft, its support, and the movable contact brush being removed.

Fig. 2, is a sectional view taken on the 55 broken lines 2—2 of Fig. 1, the parts omitted in Fig. 1, being shown in place.

Fig. 3, is a plan view of the movable contacts and their carrier.

Fig. 4, is a sectional view taken on the 60 broken line 4—4 of Fig. 3, and

Fig. 5, is a plan view of the contact plate receiving the current from the magneto.

Similar reference characters denote like parts throughout the several views.

Referring to the drawing, the body 10, of 65 the timer is substantially hollow, and externally of a shape similar to the present standard Ford timer, provided with the usual arm 11, having an opening 12 at its free end to receive the connection for adjustment to advance or retard the spark. This body is of hard fiber or like insulating material and is molded or pressed to shape, and I prefer to strengthen the arm 70 11, and the opening therein by the insertion 75 of a metallic core 13.

I also prefer to reinforce the bearing for 80 the cam shaft by molding therein a metallic tube 14. Both of these metallic reinforcements are insulated in the body 10.

The body 10, is interiorly rabbeted to 85 form an annular raceway 15, into which are seated quadrantly spaced fixed contact plates 16, 17, 18, 19. These fixed contact plates are elongated segments of a circle and are pressed into place when molding the body member and in such manner that their outer surfaces are flush with the surface of the raceway.

Each of these plates is provided at the 90 center of its outer edge with a right angle projection 20, which extends into the body 10, below the surface of the raceway, there being an opening in each projection for the purpose hereafter described.

Spaced binding posts 21, 22, are mounted on the top of the body 10, and their terminals 23, 24, pass through openings in 95 said body and enter the holes in the right angle projections of the two upper contact plates 16 and 17, making contact therewith.

The binding posts 25, and 26, for connection with the two lower fixed contact plates 18 and 19 are also mounted upon the top of the body 10, between the binding 100 posts 21 and 22.

Conductor wires or strips 27 and 28, are connected at one end to the right angle projections on the lower contact plates 18 105 and 19, preferably by eyelets 29 and 30, inserted into the holes in said projections.

These wires or strips 27 and 28 are em-

bedded into the body 10, and pass from the contact plates 18 and 19, into contact with the terminals 31 and 32 of the binding posts 25 and 26, such terminals passing through 5 openings in the fiber body 10. I have represented the upper ends of the conductors 27 and 28, as passing into recesses in the lower ends of the terminals 31 and 32.

33, denotes a rotatable disk of insulating 10 material within the body 10, and provided on its inner side with an integral hub 34, through which the cam shaft 35 passes, being secured thereto by a pin 36, or other suitable means. The end of the shaft 35, is 15 preferably threaded, upon which is screwed a lock nut 37.

This disk 33, also carries the movable contact or brush 38. Upon the outer side of the disk there is a metallic plate 39, provided 20 with a central opening surrounding the hub 34, and upon the inner side of the disk there is another metallic plate 40, also provided with a central opening for the passage of the hub 34.

25 These two metallic plates 39 and 40, are secured to the disk by screws 41 and 42, which pass through the disk.

The plate 40, is of less diameter than the disk, but has an integral projection 43, 30 which extends to the periphery of the disk at one point.

Adjacent the end of this projection 43, the plate 40 is provided with an opening 44. In register with this opening 44, in the 35 plate 40, there is an opening 45, through the disk 33, of somewhat greater diameter than the opening 44, in said plate.

The brush 38, projects through the opening 44, in the plate 40, and is provided with 40 an annular flange 46, which takes against the edge of the plate surrounding the brush and thus holds it within the openings 44 and 45. Within the opening 45, in the disk 33, and between the brush 38, and back plate 45 39, there is a spiral spring 47, which gives the brush a resilient bearing upon the surface of the raceway 15, and fixed contacts 16, 17, 18, 19, while at the same time the brush is securely retained in its carrier.

50 The plate 40, is also provided with a plurality of uniformly spaced openings 48, of predetermined diameter and with their edges beveled inwardly as shown most clearly in Fig. 4. In register with each of these 55 openings 48, there is an opening 49, through the disk 33, of somewhat greater diameter than the openings 48, in the plate 40, so that the beveled edges of the openings 48, meet the top edges of the openings 49. A 60 ball contact 50, is inserted in each of the receptacles formed by the openings 49, back plate 39, and front plate 40, which balls are of a size slightly smaller than the diameter of the openings 49, but of slightly larger diameter than the openings 48, or so that while

they may move without undue friction within the openings 49, they cannot project through the openings 48, except to a predetermined degree, being held back by the beveled edges of said openings. A spiral 70 spring 51, is provided between each of these ball contacts 50, and the back plate 39, by which said balls are each normally held projecting to the desired extent through said openings 48, in the plate 40.

75 52, indicates a bracket, provided with a central longitudinal recess 53, extending from one end to a predetermined distance from the other end of the bracket.

This bracket is firmly secured to the inside of the body member 10, by a screw or screws 54, or in any other suitable manner. An elongated metallic plug 55, is slidably fitted within the recess 53, its forward end being rounded. This plug 55, is provided with a stem 56, which projects through an opening in the closed end of the bracket, upon which projecting end is secured a contact nut 57, there being a spiral spring 58, surrounding the stem 56, between the plug 55, and the closed end of the bracket 52, by means of which the forward and rounded end of the plug is normally held projecting a predetermined distance beyond the open end of the recess 53, the nut 57, limiting the outward movement of the plug. A metallic plate 59, shaped to conform to the outer surface of the body 10, and which receives the electric current from the magneto (not shown), is secured to the body 10, by a bolt 60, and clamping nut 61.

Upon the inner end of the bolt 60, there is screwed a nut 62, provided with a contact point 63, which makes and breaks the circuit through the timer as the contact nut 57, is brought into contact therewith or drawn away from it by the spiral spring 58. It will be apparent that by this construction the make and break is allowed to travel in the advance and retard position 105 in the timer shell.

110 During the revolution of the shaft 35, carrying the disk 33, the ball contacts 50, are successively brought into contact with the plug contact 55, forcing its stem 56, inward and thereby bringing the contact nut 57, on its outer end into contact with the contact point 63, on the end of the bolt 60, thus closing the circuit to the movable contact or brush 38; this occurs at the exact 115 time that the brush has reached and is upon one end of one of the fixed contacts 16, 17, 18 or 19, and the operation is so timed that the brush reaches the opposite end of the fixed contact just as the ball contact passes from contact with the plug 55, when the expansion of the spring 58, separates the contacts 57 and 63, thus breaking the circuit, so that the brush 38, is not charged 120 with current while passing over the raceway 125

between the respective fixed contacts, whereby the pitting or burning of the brass segments forming the fixed contacts or the carbonizing of the condensite raceway of the timer is prevented, also the pitting of the carbon contact brush, thereby greatly lengthening the usefulness of the timer.

5 The spring bearings of the ball contacts and the make and break contacts provide for any lost motion or end play of the cam 10 shaft of the motor, equalizing the breaker contacts at all times.

I claim as my invention:

1. An ignition timer, comprising a casing 15 of insulating material having an interior annular raceway, a plurality of contact plates fixed therein, a rotary shaft, a brush, a holder therefor secured to the shaft, a plurality of resilient contact members spaced 20 apart in said holder, and make and break contacts co-acting therewith.

2. An ignition timer, comprising a hollow body of insulating material having an interior annular raceway, fixed contacts embedded 25 therein, a rotary shaft, a brush and holder therefor connected with said shaft, a plurality of spaced ball contacts carried by the brush holder, and make and break contact coacting with said ball contacts by 30 means of which the brush is intermittently charged with electric current.

3. An ignition timer, comprising a body 35 of insulating material having an interior annular raceway, fixed contact plates embedded therein, a rotary shaft extending into the body perpendicularly to the raceway, a disk of insulating material connected to said shaft, a brush carried by said disk, a plurality of spaced ball contacts 40 also carried by said disk, and make and break contacts whereby said brush is intermittently charged with electric current.

4. An ignition timer, comprising a body of insulating material having an interior annular raceway, spaced fixed contacts embedded therein, a rotary shaft extending into the body perpendicularly to the raceway, a disk of insulating material provided with a hub connected to said shaft, metallic plates, one upon each side of said disk 50 and secured thereto by metallic members passing through the disk, said disk having an opening adjacent its periphery, there being an aligned opening in the plate on the inner side of said disk, a brush within the 55 opening in the disk provided with an annular flange, a spring within said opening and between the brush and the metallic plate on the outer side of the disk, a plurality of spaced ball contacts within openings in said disk and projecting through aligned openings in the metallic plate on the inner side of said disk, and make and break contacts within the body member which coact with said ball contacts to intermittently charge said brush with electric current.

5. In an ignition timer for internal combustion engines, and in combination, a hollow body having an interior annular raceway, a series of fixed contacts seated therein, binding posts with terminals engaging certain of said fixed contacts, intermediate binding posts, conductors engaging their terminals and extending therefrom through the insulating material of the body into contact with the remaining fixed contacts, a rotary shaft, a brush and holder therefor connected to said shaft, a plurality of spaced ball contacts carried by the brush holder, and make and break contacts coacting with 70 said ball contacts whereby the brush is intermittently charged with electric current.

Signed by me this 19th day of May, 1921.
VANCE SHEARER.
